METALLIC FLOORING

George L. Dresser, Albany, N. Y.

Application July 11, 1935, Serial No. 30,895

5 Claims. (Cl. 14—73)

This invention relates to metallic floorings and particularly to lightweight metallic bridge floorings of the type disclosed in my pending application Serial No. 7,260, filed February 19, 1935.

The metallic flooring which comprises the subject matter of the application just referred to has a number of novel and important features of construction which render it particularly suitable for use for many purposes, but especially 10 as a bridge flooring.

Essentially the flooring referred to comprises a plurality of vertically disposed webs or supporting members which rest upon the sub-structure of a bridge or the like and a plurality of flat traffic elements bridging these members, the traffic elements being arranged in rows and the elements of each row alternating with the elements of the two next adjacent rows. The supporting members and traffic elements, therefore, 20 together form a grid-like traffic supporting surface having regularly disposed apertures therein. By preference the supporting members are disposed, when applied to a bridge or roadway, transversely of the direction of traffic and the 25 traffic elements are disposed with their major axes extending in the same general direction as the traffic. The aperture defined by each adjacent pair of traffic elements and the supporting members to which the ends of these elements 30 are attached are generally square or rectangular and defined by straight edges.

Flooring such as above described has proven 35 eminently successful in actual use and the present invention provides a flooring which is generally similar but which has a design which is somewhat modified in order to further decrease the possibility of skidding of motor vehicles progressing over its surface. Thus, in accordance 40 with the teachings of the present invention, the traffic supporting elements have either their lateral edges serrated or the elements themselves are so disposed as to present edges which are relatively inclined to the supporting members and hence inclined to the direction of traffic. Increased 45 resistance to slipping is therefore realized, which is of course desirable especially in the event that the flooring is disposed at an angle to the horizontal.

To bring about the desired increased resistance to skidding or slipping the traffic elements and supporting members may be formed in various ways of which two examples are illustrated 50 in the drawing by way of example.

55 In the drawing:

Figure 1 is a plan view of portion of a metallic flooring structure embodying the invention;

Figure 2 is a section on line 2—2 of Figure 1; and

Figure 3 is a plan view similar to Figure 1 but showing a modified form of flooring.

In the form of the invention illustrated in Figures 1 and 2 a supporting structure is rather diagrammatically illustrated at 10 and it will be understood that this supporting structure may 10 comprise the floor beams of a bridge or may comprise any other solid base or support. Mounted upon the supporting structure 10 are a plurality of supporting members, vertically disposed and spaced in parallel planes. In the 15 forms of the invention disclosed by way of example certain of these supporting members 11 are formed as I-beams and certain of them, which alternate with the I-beams 11, comprise flat metallic webs 12. The traffic contacting and 20 supporting elements are indicated at 13 and preferably these elements are generally rectangular in form, with their major axes disposed normally to the supporting members below. Preferably also the various traffic elements are formed as 25 horizontally disposed flanges integral with the supporting webs 12. Alternate elements 13 lie on opposite sides of the webs 12 of which they form portions, as clearly shown in the drawing, and the free ends of these elements 13 rest upon 30 the intermediate I-beams 11, and are welded thereto.

The supporting members 11 and 12 are welded or otherwise suitably secured to the supporting base 10 as indicated at 14 and 15, respectively, 35 and these welds, together with the welds 16 by means of which the free ends of bridging traffic elements 13 are secured to the I-beams 11, unite all parts of the metallic flooring into one integral rigid structure.

40 In Figure 1 of the drawing, the directions of traffic flow over the metallic flooring is indicated by the double headed arrow A, the wheels of vehicles moving over the flooring thus moving longitudinally of the traffic supporting elements. 45 The tires of rubber tired vehicles press downwardly into the uniformly distributed apertures the margins of which are defined by the edges of the flat upper surfaces of the I-beams 11, the side edges of adjacent traffic elements 13 and 50 the ends of the traffic elements which alternate therewith. The manner in which the tires of the pneumatic vehicle will protrude into one of these apertures is indicated in Figure 2, the outline of the tire periphery being indicated at 17. 55

For the purpose of increasing the frictional engagement of the tire and traffic engaging elements, the side edges of the elements 13 are serrated, as shown in the drawing, to provide edges which do not extend truly in the direction of traffic but which have portions inclined to the direction of traffic. The soft rubber of the tire will flow to permit the tire to conform to the serrated edges of the traffic supporting elements and these serrated edges therefore comprise means for increasing the frictional engagement of the tire and the traffic surface. The number of serrations formed upon the lateral edges of each element 13 may vary as shown in the drawing and obviously the character of the serrations may vary widely. Likewise the flat upper flanges of the I-beams 11 are preferably cut away or notched to provide arcuate tire engaging edges indicated at 18, opposite the gaps between adjacent pairs of traffic supporting elements 13. Again, the end edges of traffic elements 13 at the welds 16 may be curved, as indicated at 19, to further increase the ability of these edges to fully engage the tread surface of a rubber tire passing over the same.

If desired, the lateral edges of the traffic elements may be made straight as shown in Figure 3 and the elements themselves inclined to the directions of traffic, indicated by the double headed arrow B in this figure. Here the traffic elements 13' are shown to have straight parallel edges but these edges make substantial angles with the supporting members 11' and 12' and with the direction of traffic. Furthermore, the elements 13' integral with any one supporting web 12' are disposed angularly with respect to the elements 13' of the webs 12' on both sides of the same, the traffic surface thus presenting a "herringbone" surface to the eye and the tendency to slipping or skidding of rubber tired vehicles being furthermore decreased by this arrangement. It will be understood that the traffic elements 13 and 13' need not be necessarily integral with the webs 12 and 12' but may be formed separately and secured thereto. An economical method of fabricating the structure, however, contemplates the formation of the webs 12 and 12' and elements 13 and 13' integral with one another, the traffic elements comprising in reality flanges formed by bending over at right angles to the webs to which they are attached the narrow strips formed by cutting parallel kerfs in the edges of a flat plate, alternating narrow strips being bent in opposite directions.

Having thus described the invention, what is claimed as new and desired to be secured by Letters Patent is:

1. Metallic bridge flooring comprising a plurality of supporting webs disposed in vertical parallel planes transversely to the direction of traffic, a plurality of individual flat generally rectangular metallic elements arranged with their major axes respectively disposed in the general direction of traffic and substantially normal to the webs, said elements lying in a common horizontal plane and in parallel rows, the elements of each row being spaced apart and spaced from and alternating with the elements of adjacent rows and each element having its ends supported upon spaced adjacent webs, portions of the lateral edges of said elements being disposed at angles to the direction of traffic. 5

2. Metallic bridge flooring comprising parallel spaced elongated supporting members, a row of spaced flat elongated traffic elements bridging each pair of adjacent supporting elements, the elements of one row of elements alternating with the elements of the next adjacent rows, each such element being spaced from adjacent elements in the plane of the traffic surface, and the mutually facing edges of adjacent elements of each row of elements being serrated, for the purpose set forth. 10

3. Metallic bridge flooring comprising parallel elongated supporting members and parallel traffic elements bridging said members, each element being spaced from all adjacent elements and said elements collectively comprising a flooring having regularly distributed apertures laterally defined by spaced adjacent elements, and the adjacent edges of said last named adjacent elements being parallel and disposed at acute angles to the supporting members. 15

4. Metallic flooring comprising spaced parallel elongated supporting members having flat upper surfaces, and flat parallel traffic elements bridging the spaces between said members, and each element being spaced from all adjacent elements, thus forming a traffic surface with regularly distributed apertures, the said flat supporting members having arcuate edges which constitute marginal edges of the respective apertures. 20

5. The combination set forth in claim 4 in which those edges of the traffic elements which define the apertures are serrated. 25
